UNITED STATES PATENT OFFICE.

WILLIAM D. JEWELL, OF SALT LAKE CITY, UTAH.

SAFETY-HOOK.

SPECIFICATION forming part of Letters Patent No. 674,383, dated May 21, 1901.

Application filed September 26, 1900. Serial No. 31,163. (No model.)

To all whom it may concern:

Be it known that I, WILLIAM D. JEWELL, a citizen of the United States, residing at Salt Lake City, in the county of Salt Lake and State 5 of Utah, have invented new and useful Improvements in Safety-Hooks, of which the following is a specification.

My invention relates to safety-hooks adapted especially for use with hoisting apparatus; 10 and the object of the invention is to provide a simple and inexpensive device of this character which will effectually prevent the accidental detachment of the hook from the hoisting-ropes or other device with which it is used.

15 The construction of the improvement will be fully described hereinafter in connection with the accompanying drawings, which form a part of this specification.

In the drawings, Figure 1 is a side elevation 20 of the hook in closed position. Fig. 2 is a similar view of the hook in its open position, and Fig. 3 is a side elevation with one side of the movable slide or casing of the hook removed.

25 The reference-numeral 1 designates the shank or body of the device formed at one end with an integral hook 2 and at its opposite end with a head 3, to which is secured a bail 4 by means of a pin 5.

30 The body 1 is formed adjacent to its outer end with a flange 6, which serves as a stop to limit the movement of the movable member of the device, as will be further referred to hereinafter.

35 7 designates a slide comprising a plate or casting of U form in cross-section, which encompasses the body 1 and projects beyond the latter. Between the edges of the slide 7, adjacent to the hook, is rigidly secured a block 40 8, having a curved projection 9, which is adapted to abut against the end of the hook 2 and form in connection therewith a closed ring, as shown in Figs. 1 and 3.

45 10 designates a lever pivotally secured between the sides of the slide 7 by means of a pin 11 and formed with an elongated slot 12, through which extends a cross-pin 13, the ends of which are secured to the side walls of the slide.

50 The outer end of the lever 10 is formed with a loop or ring 14, and the inner edge of said lever is formed with a dog or lug 15, adapted

to enter a groove 16, formed in the inner edge of the body 1. This dog or lug 15 is normally held in engagement with the groove 16 by 55 means of a flat spring 17, one end of which is secured by a set-screw 18 or equivalent means to the outer side of the block 8, while its free end bears against the outer side or edge of the lever. 60

The operation and utility of the device constructed as above described will be readily understood. When the slide (with its attached block and lever) is in the position shown in Figs. 1 and 3, the dog 15 is firmly 65 held in engagement with the groove 16 by the force of the spring 17, and the hook cannot open by the accidental movement of the slide and block. When the lever 10 is tilted upon its fulcrum-pin 11 by means of a tripping-rope attached to the loop 14, the spring is 70 lifted and the slide may be moved until the dog or lug 15 strikes the stop-flange 6. When the slide is moved back to close the hook, the spring automatically locks the dog in engagement with the body 1. 75

I claim—

1. A safety-hook comprising a body portion formed with a hook at one end and with a groove adjacent to its opposite end; a slide 80 movable on said body portion; a block rigidly secured between the sides of said slide; a lever fulcrumed between the sides of the slide and formed with an elongated slot and a dog or lug; a cross-pin for limiting the 85 movement of said lever; and a spring secured at one end to said block and having its opposite free end bearing against said lever.

2. A safety-hook comprising a body portion formed with an integral hook; a U-shaped slide through which said body portion extends; a block rigidly secured between the sides of the slide, and having a curved projection; a lever fulcrumed between the sides of the slides and formed with an elongated slot and a projecting lug or dog adapted to enter a corresponding groove in the body of the hook; a spring secured at one end to said block and bearing at its opposite end against said lever; and a stop projecting 95 from the body portion and adapted to engage said dog to limit the movement of the slide. 100

3. A safety-hook comprising a body portion formed at one end with an integral hook

and at its opposite end with a head and having a groove adjacent to the head; a pail secured to said head; a slide through which said body portion extends; a block rigidly secured between the sides of said slide and having a curved extension; a lever fulcrumed between the sides of the slide and having an elongated slot, a projecting lug or dog, and a loop or ring; a spring secured at one end to

5

10 said block and bearing upon said lever; and

a projection on said body portion adapted to contact with the dog on the lever to limit the movement of the slide.

In testimony whereof I affix my signature in presence of two witnesses.

WILLIAM D. JEWELL.
